S. P. GREENE

JACKET FOR SAND MOLDS

Filed Sept. 4, 1923

INVENTOR.
Samuel P. Greene
D. C. Christie
ATTORNEY.

UNITED STATES PATENT OFFICE.

SAMUEL P. GREENE, OF DAYTON, OHIO, ASSIGNOR TO THE STANDARD FOUNDRY COMPANY, OF DAYTON, OHIO.

JACKET FOR SAND MOLDS.

Application filed September 4, 1923. Serial No. 660,851.

To all whom it may concern:

Be it known that I, SAMUEL P. GREENE, a citizen of the United States, residing in Dayton, in the county of Montgomery and State of Ohio, have invented certain new and useful Improvements in Jackets for Sand Molds or the like, of which the following is a specification, reference being had therein to the accompanying drawings.

10 This invention relates to improvements in jackets for sand molds used in casting metal.

The object of the invention is to provide integral cast iron jackets as a substitute for wood or sheet metal jackets which are used for supporting the sand molds after the same have been removed from the flasks while the metal is being poured into the molds.

20 Wood jackets, which are commonly used for this purpose, require constant upkeep due to burning of the wood by coming in contact with the hot metal, also due to the tendency of the jackets to be rendered out of shape through warping of the wood and 25 the rough usage which foundry equipment receives, this latter difficulty being also experienced with sheet metal jackets which renders sheet metal jackets impracticable for general use as a substitute for wood 30 jackets.

The improved cast iron jacket of the present invention effectually overcomes the difficulties as it retains its shape and is practically indestructible under any conditions 35 of use.

While the cast iron jackets may be made from any suitable pattern, it has been found desirable in the practice of the invention to use the flask, in connection with which each 40 set of jackets is to be used, as the pattern for the jackets in order to obtain an approximate duplication of inner dimensions in the jacket to the corresponding dimensions of the flask.

45 In the accompanying drawings:

Fig. 1, is a side view of the improved jacket,

Fig. 2, is a plan view,

50 Fig. 3, is a side view of the jacket as applied to a sand mold.

Fig. 4, is a cross-sectional view through the sand mold and cores as arranged for pouring the metal.

Fig. 5, is a view of a flask, partly in broken section, showing the manner of using a flask as a pattern for the jackets.

As here shown the jacket is an integral rectangular shaped casting, —1, conforming to the shape of a flask. Flanges 2 and —3, are formed on the four sides of the jacket 60 flange —2 serving as a hand hold for raising and lowering the jacket relative to the sand mold, and flange —3 as a base for the jacket, both flanges acting to strengthen the jacket and to keep the sides straight in 65 casting.

The jackets are made in sets, each set conforming in inside length, width and taper to the sand flask in connection with which the jackets are to be used. While any suitable pattern may be used for producing the jackets, the best results are obtained, and with reduced pattern cost, by using the sand flasks as patterns. By adding a bottom extension —4, to a flask —5, as indicated in 70 Fig. 5, of the drawings, to compensate for shrinkage of the metal in casting, the inside dimensions in length, breadth and taper of the flask can be closely approximated in the jacket castings made from it, the height, 75 so thickness of the walls and external conformation of the castings being determined by using suitable cores, as indicated in Fig. 4, in preparing the molds.

Having described my invention, I claim:

1. The herein described method of casting jackets for sand molds consisting in adapting a sand flask as the pattern for a jacket, in using the flask so constructed to form the inner part of a sand mold for the jackets, in arranging cores relative the said inner part to complete the mold and in casting a jacket therein.

2. The herein described method of casting jackets for sand molds consisting in adapting a sand flask as the pattern for a jacket, by adding an extension of the flask to the bottom thereof, in using the flask as constructed to form the inner part of a sand mold for the jackets, in arranging cores 100

relative to said inner part to complete the mold and in casting a jacket therein.

3. The herein described method of casting jackets for sand molds consisting in adapting a common sand flask as the pattern for a jacket, in supporting the flask in raised position relative to the inner sand mold for the

jacket to compensate for shrinkage of the metal in casting with respect to the taper of said jacket, in arranging cores externally to complete said mold and in casting a jacket therein. ¹⁰

In testimony whereof I affix my signature.

SAMUEL P. GREENE.
